Primary Examiner — Rashida C. Walshon(74) *Attorney, Agent, or Firm* — Knobbe, Martens, Olson & Bear LLP(57) **CLAIM**

The ornamental design for a heel protector, as shown and described.

DESCRIPTION

FIG. 1 is a perspective view of a first embodiment of a heel protector showing my new design.

FIG. 2 illustrates the perspective view thereof in use on a shoe heel.

FIG. 3 is a front elevational view thereof. Right-side elevational, left-side elevational and rear elevational views thereof are identical to the front elevational view.

FIG. 4 is a top plan view thereof.

FIG. 5 is a first variation of a bottom plan view thereof; and, FIG. 6 is a second variation of a bottom plan view thereof. The evenly broken lines throughout the drawings indicate environmental and optional features such as treads and grips, that form no part of the claimed design.
